(57) **CLAIM**

The ornamental design for an over the door hook, as shown and described.

DESCRIPTION

FIG. 1. is a first perspective view of an over the door hook showing my design;

FIG. 2. is another perspective view thereof;

FIG. 3. is a front perspective view thereof;

FIG. 4. is a back perspective view thereof;

FIG. 5. is a right perspective view thereof;

FIG. 6. is a left perspective view thereof;

FIG. 7. is a top perspective view thereof; and,

FIG. 8. is a bottom perspective view.

The broken lines depict the over the door hook in an environment of use and form no part of the claim.
